UNITED STATES PATENT OFFICE.

WILLIAM L. SHARP, OF STEUBENVILLE, OHIO, ASSIGNOR TO THE OHIO FOUNDRY AND MANUFACTURING CO., OF STEUBENVILLE, OHIO, A CORPORATION OF OHIO.

DESIGN FOR A RADIANT FOR GAS HEATERS.

Application filed August 2, 1927. Serial No. 22,978. Term of patent 7 years.

To all whom it may concern:

Be it known that I, WILLIAM L. SHARP, a citizen of the United States, residing at Steubenville, in the county of Jefferson, State of Ohio, have invented a new, original, and ornamental Design for a Radiant for Gas Heaters, of which the following is a specification, reference being had to the accompanying drawing, forming a part thereof.

The figure is a front perspective view of a radiant, showing my new design.

The dominant features of the design reside in the termination of the ends of the ribs flush with the outer surfaces of the walls and in the shape of the lower front portion of the radiant, which portion is widened in its vertical plane, and which is of reduced length horizontally, relative to the over-all width of the body of the radiant.

I claim:

The ornamental design for a radiant for gas heaters, as shown and described.

WILLIAM L. SHARP.
